US00D979671S

(12) **United States Design Patent** (10) **Patent No.:** **US D979,671 S**
(45) **Date of Patent:** **** Feb. 28, 2023**

(54) **CROSSFIT GYMNASTICS GRIP**

(71) Applicant: **VICTORY GRIPS LLC**, Tybee Island, GA (US)

(72) Inventor: **Victor Brian Pellegrino**, Tybee Island, GA (US)

(73) Assignee: **VICTORY GRIPS LLC**, Tybee Island, GA (US)

(**) Term: **15 Years**

(21) Appl. No.: **29/794,358**

(22) Filed: **Jun. 11, 2021**

(51) LOC (14) Cl. **21-02**

(52) U.S. Cl.

USPC **D21/684; D2/610**

(58) **Field of Classification Search**

USPC D2/610, 611, 617, 619; D29/113, 114,

D29/117.1, 117.2, 120.1; D21/684, 797

CPC A41D 13/08; A41D 19/00; A41D 20/00;

A41D 13/088

(57) **CLAIM**

The ornamental design for a crossfit gymnastics grip, as shown and described.

DESCRIPTION

FIG. 1 is a perspective view of an open configuration of my crossfit gymnastics grip.

FIG. 2 is a front view thereof.

FIG. 3 is a back view thereof.

FIG. 4 is a left side view thereof.

FIG. 5 is a right side view thereof.

FIG. 6 is a top view thereof.

FIG. 7 is a bottom view thereof.

FIG. 8 is a perspective view of a closed configuration of my crossfit gymnastics grip.

FIG. 9 is a front view thereof.

FIG. 10 is a back view thereof.

FIG. 11 is a left side view thereof.

FIG. 12 is a right side view thereof.

FIG. 13 is a top view thereof; and,

FIG. 14 is a bottom view thereof.

The dotted dash lines shown in the figures are for the purpose of showing stitching, which form no part of the claimed design. The broken lines in each figure illustrate graphical environmental features that form no part of the claimed design.

1 Claim, 8 Drawing Sheets
